United States Patent Office

Des. 214,794
Patented July 29, 1969

214,794

COMBINED PORTABLE DICTATING AND TRAN- SCRIBING MACHINE OR SIMILAR ARTICLE

Peter Quay Yang, New York, N.Y., assignor to The Gray
Manufacturing Company, a corporation of Connecticut

Filed June 4, 1968, Ser. No. 12,205

Term of patent 7 years

Int. Cl. D14—01

U.S. Cl. D26—14

FIG. 1

FIG. 2

FIG. 3

FIG. 4

FIG. 5

FIG. 6

FIG. 7

FIG. 8

FIGURE 1 is a front perspective view of a combined portable dictating and transcribing machine or similar article;

FIGURE 2 is a perspective view thereof in an alternate position;

FIGURE 3 is a top plan view;

FIGURE 4 is a bottom plan view;

FIGURE 5 is a front elevational view;

FIGURE 6 is a rear elevational view thereof;

FIGURE 7 is a left end elevational view; and

FIGURE 8 is a right end elevational view.

I claim:

The ornamental design for a combined portable dictating and transcribing machine or similar article, as shown.
